UNITED STATES PATENT OFFICE.

FRANZ WLACH, OF VIENNA, AUSTRIA-HUNGARY.

LANTERN.

SPECIFICATION forming part of Letters Patent No. 315,875, dated April 14, 1885.

Application filed November 6, 1884. (No model.) Patented in Belgium April 15, 1884, No. 64,665; in Austria-Hungary April 22, 1884, No. 7,344 and No. 17,628, and in France July 15, 1884, No. 161,271.

To all whom it may concern:

Be it known that I, FRANZ WLACH, a citizen of Austria-Hungary, residing at Vienna, in the Province of Lower Austria and Empire 5 of Austria-Hungary, have invented new and useful Improvements in Lanterns, (for which I have obtained patents in Austria, No. 7,344, bearing date April 22, 1884; in Hungary, No. 17,628, bearing date April 22, 1884; in Belgium, No. 64,665, bearing date April 15, 1884, and in France, No. 161,271, bearing date July 10, 1884,) of which the following is a specification.

This invention relates to a lantern which can 15 be used in the open air and which can be swung about without danger that the flame may be extinguished.

The peculiar and novel construction of the 20 parts of my lantern whereby the above results are obtained is pointed out in the following specification and claims and illustrated in the accompanying drawings, in which—

Figure 1 represents a vertical section of the 25 lantern complete. Fig. 2 is a side view of the burner detached. Fig. 3 is a transverse section of the same in the plane xx , Fig. 4. Fig. 4 is a plan or top view.

Similar letters indicate corresponding parts.

In the drawings, the letter A designates a 30 jacket of cylindrical or any other suitable form. In the interior of this jacket, at a short distance above its bottom edge, is secured a concave plate, b, and the rim c beneath this plate is perforated with a large number of holes. Near the top of the jacket A is a circular shoulder, d, and beneath this shoulder is 35 situated an annular foraminous plate, e.

B is the oil-fountain. From this fountain 40 projects a foraminous flange, f, which, when said fountain is placed into the jacket A, bears upon the shoulder d. The bottom part of the fountain is contracted, and extends through an opening in the concave plate b of the jacket, leaving an annular air-passage, g, the object 45 of which is hereinafter more fully explained.

The oil-fountain is retained upon the shoulder d by a cap, C, which fits into the top of the jacket A, and is held in position by one or more spring-latches, h.

50 D is the wick-tube, which is secured in the

fountain B by a screw-thread or other suitable means, and on this wick-tube is placed the cone E. This cone is composed of two side plates, i, and two base-strips, j, and it is attached to the burner by means of sleeve k. 55 (Best seen in Figs. 2 and 3.) The side plates, i, are provided with openings l, and they come close together at the top, so that a transverse section of my cone has some resemblance to an ordinary burner-cone, as shown in Fig. 3; 60 but by referring to Fig. 4 it will be seen that an open-air passage, m, is left between the side plates, i, in the direction transversely to the base-strips j, and that said passage is gradually increasing in width from the top downward, and 65 by the openings l air is admitted to the flame in a direction at right angles to the air-passage m above named. At the same time a free supply of air reaches the flame from below, such air being admitted through the holes in the 70 bottom part of the jacket A, whence it passes through the air-passage g into the space surrounding the oil-fountain and thence through the foraminous plates e f and the cap C into the space beneath the cone E. It will be seen 75 from this description that the air which is admitted through the bottom part of the jacket in its passage to the burner circulates around the oil-fountain so as to keep the same cool and to prevent the formation of gases, and at the 80 same time the atmospheric air passes beneath the cone E not only from below, but also through the air-passage m and the openings l, and a bright flame is obtained without the use of a chimney. The foraminous plates e f are 85 used to prevent the flame from being extinguished by wind or by rapid movements of the lantern.

With the jacket A is connected the guard-frame F, which is made of wire or other suitable material, and which consists, essentially, of the bottom plate, n, the top plate, o, and the wires p, the bottom plate, n, being connected to the jacket A by a hinge-joint, q, so that the guard-frame can be swung back to 95 give access to the lamp.

Between the plates n and o is secured the globe G, or instead of a globe a series of detached glass panes may be used, the same as in lanterns now in common use. The top plate, 100

o, supports the chimney H, which consists of the spout r, the bell s, and the hood t, the bell and the hood being supported by strips u, which are fastened on the interior of the spout r. The bottom part of the bell overlaps the mouth of the spout, and the hood overlaps the top part of the bell, so that the products of combustion can escape freely from the interior of the lantern, while the flame is protected 10 against the influence of wind.

I is the handle.

My lantern can be used with advantage in the service of railways and fire-departments, and generally in the open air.

15 I am aware that a lamp-burner has been composed of side plates having their upper edges adjacent to and above the wick-tube, so that a transverse air-passage is created to admit air to the base and sides of the flame and 20 around the wick-tube.

I am also aware that a lantern has been constructed in which breaks or deflectors are arranged in the air passages and chambers used to conduct air to the burners from the base of 25 the lantern. Such features, therefore, I do not claim.

What I claim as new, and desire to secure by Letters Patent, is—

1. In a lantern, the combination of the jacket 30 A, having the bottom plate, b, having a central opening, the oil-fountain B, suspended in the jacket and having its base arranged in the opening of the bottom plate to form the annular air-passage g, the upper and lower an-

nular foraminous plates, f and e, interposed between the jacket and the fountain, and a burner, substantially as described. 35

2. In a lantern, the combination of a shell, A, having an apertured bottom plate, b, and provided adjacent to its upper edge with a shoulder, an annular foraminous plate, e, secured to the shell below the shoulder, and an oil-fountain having an attached annular foraminous plate, f, suspending the fountain from the shoulder, said fountain and apertured bottom plate being arranged to form the air-passage g, substantially as described. 40

3. The combination, substantially as hereinbefore described, with the fountain B and the jacket A, of the air-passage g, the air-space 50 surrounding the fountain, the foraminous plates e f, the wick-tube D, the side plates, i, openings l, and air-passage m.

4. The combination, with the wick-tube D, of the cone consisting of the sleeve k, the base strips j j, connected with the sleeve, and the side plates, i i, provided with the openings l l, and having their upper ends arranged adjacent to each other and constituting between them the free air-passage m, transversely to the base strips, substantially as shown and described. 55

In testimony whereof I have hereunto set my hand in the presence of two subscribing witnesses.

FR. WLACH.
